Manufacturer,
his ATTORNEY.

UNITED STATES PATENT OFFICE.

GEORGE BRAND, OF BROOKLYN, NEW YORK.

CORNER-BLOCK FOR BED-SPRING FRAMES.

SPECIFICATION forming part of Letters Patent No. 783,673, dated February 28, 1905.

Application filed December 23, 1903. Serial No. 186,296.

To all whom it may concern:

Be it known that I, GEORGE BRAND, a citizen of the United States, residing at Brooklyn, Kings county, in the State of New York, have 5 invented certain new and useful Improvements in Corner-Blocks for Bed-Spring Frames, of which the following is a specification.

My invention relates to corner pieces or blocks for bed-spring frames and the like, and 10 has for its object to provide an improved corner piece or block for use in such structures and wherein the sharp corners usual in such corner-pieces are avoided.

To these and other ends, which will herein- 15 after appear, my invention consists in the novel features of improvement and details of construction hereinafter described, and summarized in the appended claims.

Reference is to be had to the accompanying 20 drawings, forming part of this specification, wherein—

Figure 1 is a plan view of a corner piece or block embodying my invention. Fig. 2 is an 25 end elevation thereof. Fig. 3 is a plan of the inner face thereof; and Fig. 4 is a perspective view of a corner of a bed-spring frame, showing my improved corner piece or block applied.

Similar letters of reference indicate corre- 30 sponding parts in the several views.

My improved corner-piece is preferably made of a single casting of metal, and, as shown in the drawings, A is the side wall or body thereof, which at its lower end is provided 35 with a horizontally-disposed socket a, into which the side bar or rail B of the bed-spring frame is adapted to be seated. Extending from the said socket longitudinally and as a continuation thereof is a semicircular or seg- 40 mental extension a', adapted to partly embr- ace or surround the bar B, and the inner face of this extension is depressed, so as to provide a space or recess between it and the bar B for the insertion of the shanks of aux- 45 iliary supporting-springs, such as shown in United States Letters Patent Nos. 725,030 and 725,031, dated April 14, 1903, granted to me. Extending outwardly from the top edge of 50 the wall or body A and at substantially a right angle thereto is a ledge or bracket C,

provided with a rounded or curved edge d, as shown in Figs. 1 and 4. Upon the body A is shown a fin or web a'', cast integral with the same and with the ledge C for bracing the same. Extending from the top of the body A 55 at right angles thereto and opposing the ledge C and horizontally disposed with relation therewith is an extension or bracket D of angular cross-section, to which the angle or end bars D' of the frame are adapted to be se- 60 cured in the usual manner by screw-bolts or the like, and extending inwardly and downwardly from the said bracket D is the curved end wall E of the corner-piece, the lower por- 65 tion thereof constituting the head or seat of the socket a, against which the end of the bar B impinges.

F indicates the wire or spring fabric, and G 70 H plates or strips between which and the top of my corner-piece the same is secured in suit- able manner.

It will be seen that when applied to the bed- 75 spring frame my improved corner-piece pro- vides a rigid connection for the end and side bars of the frame and presents a corner with- out any sharp projections by which fabrics coming in contact therewith are apt to be torn.

Having now described my invention, what I 80 claim, and desire to secure by Letters Patent, is—

1. A corner piece or block for frame struc- 85 tures, comprising the body portion A, a hori- zontally-disposed socket a at its lower end, a ledge or bracket C having an outer curved edge extending outwardly from the top of the body A, a bracket D also extending from the top of the body A at an angle thereto, and the inwardly-curved end wall E depending from the bracket D, the lower portion of which constitutes the head or seat of the socket a, 90 substantially as described.

2. A corner piece or block for bed-spring 95 frames and the like, comprising a body por- tion, a horizontally-disposed socket at the lower end thereof, a horizontally-disposed out- wardly-projecting ledge at the top, and a bracket or ledge, opposite to the first-named ledge, projecting from the said body portion at substantially a right angle thereto.

3. A corner piece or block for bed-spring 100

- frames and the like, comprising a body portion, a socket at the lower end thereof, a horizontally-disposed ledge extending from said body portion at the top having a rounded outer edge, and a segmental extension or support extending outwardly from said socket, the same being provided with a depression, substantially as and for the purpose herein shown and described.
- 10 4. A corner piece or block for bed-spring frames and the like, comprising a body portion, a socket at the lower end thereof, a horizontally-disposed ledge projecting from the top, a bracket or ledge opposite to the first-named ledge and in a plane substantially parallel therewith, and a vertically-disposed fin or web for bracing the first-named ledge, substantially as described.
- 15 5. A corner piece or block for frames, consisting of a single casting comprising a body portion, a horizontally-disposed socket at the

lower end thereof, an outwardly-projecting ledge at the top having a curved outer edge, and an oppositely-disposed angle-bracket in a plane substantially parallel therewith, substantially as described.

6. In a bed-spring frame, the combination with the side and end bars, of a corner-piece provided with a horizontally-disposed socket engaging the side bar, an outwardly-projecting ledge at the top provided with a curved outer edge, and an oppositely-disposed ledge or bracket whose upper surface is in a plane substantially parallel with the upper surface of the outwardly-projecting ledge to which the end bar of the frame is adapted to be secured, substantially as described.

GEORGE BRAND.
